UNITED STATES PATENT OFFICE.

ROY A. WEAGANT, OF ROSELLE PARK, NEW JERSEY, ASSIGNOR TO MARCONI WIRELESS TELEGRAPH COMPANY OF AMERICA, A CORPORATION OF NEW JERSEY.

RECEIVER OF ELECTRICAL OSCILLATIONS.

1,257,657.

Specification of Letters Patent. Patented Feb. 26, 1918.

Application filed June 18, 1914. Serial No. 845,761.

To all whom it may concern:

Be it known that I, ROY A. WEAGANT, a citizen of the United States, residing in Roselle Park, in the county of Union, State of New Jersey, have invented certain new and useful Improvements in Receivers of Electrical Oscillations, of which the following is a description.

My invention relates to apparatus for receiving and detecting electrical oscillations, and is particularly useful in receiving and detecting the electrical oscillations used in wireless telegraphy. This, however, is not its only use, since it may be used in connection with other apparatus in which electrical oscillations are to be detected as, for instance, in wire telegraphy or in wireless or wire telephony. Nor is my invention limited to any particular kind of electrical oscillations, since it may be used to receive and detect a variety of different kinds of oscillations produced in various ways.

I shall describe my invention in connection with the receiving end of a wireless telegraph system in which a circuit tuned to the group frequency of the received oscillations is used.

It is well known that in such apparatus, having a circuit tuned to the group frequency of the received oscillations, the strength of the received signals is greatly diminished, and one of the objects of my invention is to correct this diminution of the signals, bringing them back to approximately the strength that they would have were the circuits tuned to wave frequency only.

In the drawings accompanying my specification I have shown at 1 an aerial; at 2 an aerial tuning inductance; at 3 the primary of an oscillation transformer; and at 4 the earth or other suitable capacity. While I have shown an inductive coupling between the primary and secondary circuits through the oscillation transformer, this coupling may be direct or conductive, or static.

The secondary circuit, which is connected to the secondary of the oscillation transformer 5, consists of two circuits shunted about the secondary 5, one containing the variable condenser 12 and the other containing the condenser 7 and the detector 6 in series, a variable condenser 11, inductance 10 and telephone 9 shunting the condenser

7 and a variable inductance 8, shunting the detector.

Any suitable form of detector may be used instead of the crystal detector illustrated and any suitable indicating instrument may be substituted for the telephone 9.

It will thus be seen that the secondary circuit comprises a circuit containing the secondary of the oscillation transformer 5 and the variable condenser 12, which circuit is preferably tuned to the wave frequency, and a circuit comprising the variable condenser 11, variable inductance 10 and telephone 9, detector 6 and variable inductance 8 connected in parallel, and the secondary of the oscillation transformer 5, which is preferably tuned to the group frequency of the oscillations received. The effect of the secondary of the transformer 5 upon the tuning of the last mentioned circuit is practically negligible because the value of the inductance of this secondary is very small as compared to that of the inductances 8 and 10. While I do not wish to limit myself to any particular ratio between the various inductances, it may be stated that good results are obtained by making the inductances 8 and 10 of substantially the same order, and each of them about 1000 times the inductance of the secondary 5.

I cannot state with certainty the theory upon which my improved circuit operates. It has occurred to me, however, that the effect of the impedance 8 upon the operation of the circuit may be as follows: The detector 6, while permitting the passage of impulses in one direction tends to prevent their passage in the other direction and thus interferes with the oscillation of the circuit. By placing an impedance in shunt with the detector, however, a path is provided for the passage of oscillations in both directions, thus improving the operation of the circuit. The impedance 8 being of relatively high value, does not, however, interfere with the operation of the detector in the case of high frequencies.

In the operation of my improved device, I may proceed as follows: I first tune the aerial circuit 1, 2, 3, 4 and the circuit containing the inductance 5 and condenser 12 to the wave frequency of the received oscillations. I then vary the value of the condenser 11 and the inductance 10 to tune to group frequency, and then vary the value of 110

inductance 8 until the maximum response is obtained in the telephone 9.

While I have shown only one form my invention may take, I do not wish to limit myself to this particular form, since it is shown merely by way of illustration and, as I have pointed out, it may be greatly varied without departing from the spirit of my invention.

10. What I claim is:

1. In a receiver of electrical oscillations, a secondary circuit including a circuit tuned to the group frequency of the received oscillations, and containing a detector and an indicating device, in combination with an inductance in shunt with the detector and in series with the indicating device.

2. In a receiver of electrical oscillations, a secondary circuit including a circuit tuned to the wave frequency of the received oscillations, and a circuit tuned to the group frequency of the received oscillations, and containing a detector and an indicating device, in combination with an inductance in shunt with the detector and in series with the indicating device.

25. 3. In a receiver of electrical oscillations,

an open oscillating circuit tuned to the wave frequency of the received oscillations, and a secondary circuit coupled thereto, and including a circuit tuned to the group frequency of the received oscillations, and containing a detector and an indicating device, in combination with an inductance in shunt with the detector and in series with the indicating device.

4. In a receiver of electrical oscillations, an open oscillating circuit tuned to the wave frequency of the received oscillations, and a secondary circuit coupled thereto and including a circuit tuned to the wave frequency of the received oscillations, and containing a detector and an indicating device, in combination with an inductance in shunt with the detector and in series with the indicating device.

In witness whereof I have hereunto signed my name in the presence of two witnesses on this 17th day of June, 1914.

ROY A. WEAGANT.
